UNITED STATES PATENT OFFICE

2,157,201

TITLE AND MEANS FOR SETTING THE SAME

Carl F. Glaser, Chicago, Ill.

Application January 17, 1938, Serial No. 185,274

17 Claims. (Cl. 72—9)

My invention includes an improved construction of tile of ceramic or other material, for finishing the interior and exterior surfaces of the walls of buildings, by which the tiles are provided on their back faces, with first projecting and spaced lugs having vertically extending apertures therethrough cooperating with the setting or mounting devices to effect three desirable results: first, to automatically align the tiles in horizontal rows without care on the part of the workman; second, to mechanically hold the tiles in proper position on the wall being finished therewith, during the time required for the cement or mortar employed in mounting the tiles, to set or harden; and third, to automatically align the tiles in vertical rows without care on the part of the workman.

My invention also includes novel forms of metal mounting clips made preferably by bending metal wires or rods, and horizontal mounting strips of any desired material, although I find that from the standpoint of cheapness, ease of erection, and effectiveness in use, said strips are quite satisfactory when made of wood. Said mounting strips are enough narrower than the distance vertically between the said first lugs on the tile, to facilitate mounting said tiles on said strips so that the weight of said tiles will be carried by said strips during the setting or hardening of the cement or mortar used to mount said tiles, said strips having first been erected on the wall surface in horizontal position by suitable fastening devices, for example, nails, and spaced vertically according to the height of the tiles to be mounted thereon. Said mounting strips are preferably provided along the upper portion of their wall surfaces, with grooves or rabbets to freely receive parts of said clips after said strips have been secured to the wall.

In addition to the first lugs referred to, my improved tiles are also preferably provided with second lugs on their rear or mounting surfaces, to interlock with the cement or mortar used in mounting the tiles, to increase the security and rigidity of their attachment to the walls receiving them.

In using my improved tiles and tile mounting means, the mounting strips are first secured to the wall in horizontal position and spaced vertically according to the size of the tiles to be mounted thereon, to receive and support successive horizontal rows of the tiles with their meeting edges closely adjacent each other; the tiles are then dressed on their rear faces with the mounting cement or mortar employed, and placed

on the erected mounting strips, with the mounting clips in the apertured first lugs of the tiles and also in the grooves or rabbets of the strips, thereby securely supporting the weight of the tiles and holding them snugly against the wall in proper position until the cement or mortar has hardened or set, which makes the mounting of the tiles permanent. At the same time, each successive horizontal row of tiles engages the upwardly projecting ends of the mounting clips of the next lower row of tiles, and in this manner the tiles are placed automatically in aligned vertical rows. This eliminates much time and labor now required in setting tiles, and makes the operation correspondingly cheaper.

My invention will be best understood by reference to the accompanying drawing illustrating a preferred embodiment thereof, in which

Fig. 1 shows in front elevation, a plurality of my improved tiles mounted on a wall by my improved mounting means,

Fig. 2 shows in right hand end elevation, the mounted tiles illustrated in Fig. 1,

Fig. 3 illustrates in rear elevation to an enlarged scale, one of my improved tiles,

Fig. 4 is a bottom view of the tile shown in Fig. 3,

Fig. 5 is a right hand end elevation of the tile shown in Fig. 3,

Fig. 6 shows in a view similar to Fig. 2 and to an enlarged scale, one of the mounting strips on a wall before mounting the tiles thereon,

Fig. 7 shows in front elevation one of my improved mounting clips, to an enlarged scale from that shown in Fig. 1,

Fig. 8 is a right hand end elevation of the clip shown in Fig. 7, and

Fig. 9 shows in a view similar to Fig. 7, a modified form of mounting clip.

Similar numerals refer to similar parts throughout the several views.

As shown in Figs. 3, 4 and 5, my improved tile consists of a body portion 10 from the corner portions of the back surface of which, first mounting lugs 11, 12, 13 and 14 project, said lugs having apertures 11a, 12a, 13a and 14a extending vertically through them respectively and substantially in line with the back surface of the body portion 10. Said lugs preferably are of the same size as each other and project the same amount from the body portion 10 to space the tile a sufficient distance from the wall surface on which the tile is to be mounted, to accommodate the mounting strip below described. Additionally, said lugs at the upper edge of the tile

and their said apertures, preferably have the same horizontal spacing as the said lugs at the lower edge of said tile and their apertures, thereby providing for supporting a first tile by said 5 upper lugs and also providing for engaging a second tile above said first tile to aline said tiles in a vertical row by the apertures in said lower lugs on said second tile, the lower surfaces of the upper lugs of each tile being substantially in line 10 with each other, as are also the upper surfaces of the lower lugs of said tile, and the upper lugs of each tile being substantially parallel with the lower lugs of said tile, so that the tile may be mounted with either pair of said first lugs uppermost with the same result, the alined lower surfaces of said upper lugs, for either way the tile may be turned and mounted, affording surfaces of substantial area reliably supporting the tile in proper position in mounting it on a wall.

20 In addition to said first lugs, as shown in Figs. 3, 4 and 5, the body portion 10 of the tile is also provided with second spaced lugs 15 and 16 in horizontal rows between the upper first lugs 11 and 12 and the lower first lugs 13 and 14 respectively, the lower surfaces of the lugs 15 being in line horizontally with the lower surfaces of the lugs 11 and 12, and the upper surfaces of the lugs 16 being in line with the upper surfaces of the lugs 13 and 14, said second lugs projecting 25 substantially the same amount from back of the body portion 10 as said first lugs, and having substantially less vertical extent than said first lugs. Said second lugs increase the supporting surface for mounting the tile, they provide additional 30 gauging projections for spacing the body portion of the tile from the wall on which it is mounted, and they also serve to positively anchor the mounted tile to the wall when the cement or mortar used has hardened. The lower surfaces 35 of the upper lugs 11 and 12 are provided with grooves 11b and 12b extending rearwardly from the lower end of the apertures 11a and 12a respectively, and the upper surfaces of the lugs 13 and 14 are provided with similar grooves 13b 40 and 14b extending rearwardly respectively from the upper ends of the apertures 13a and 14a, the upper ones of said grooves serving to receive the mounting clips 20 as below described, depending upon which of said first lugs happen to 45 be uppermost when the tile is mounted on the wall, it being immaterial which of the two opposite mounting edges is selected as the uppermost edge in mounting the tile, since said two mounting edges are substantially the same and are interchangeable.

50 In mounting the tiles as shown in Figs. 1 and 2, mounting strips 17, for example, of wood, are first secured in horizontal position to the wall 18 to be covered with the tiles, by suitable fastening devices, for example, nails 19, the spacing vertically of said strips, from the top edge of each strip to the top edge of the next strip, being equal to the height of the tiles and any additional amount allowed for cement or mortar between 55 the edges of the tiles. Each of the strips 17 is substantially narrower vertically than the vertical distance between the lugs on the back of each tile, to facilitate the use of the mounting clips employed, and each of said strips is slightly 60 thinner than the extent of horizontal projection of the lugs from the back surfaces of the tiles 10, to insure the resting of said lugs against the wall 18, thereby accurately locating the outer surfaces of the tiles in a plane surface parallel 65 with the surface of the wall. Furthermore, as

more clearly shown for one of the strips 17 in Fig. 6 before the tiles are mounted thereon, each of said strips is provided in the upper part of its back surface, with a groove or rabbet 17a extending through the upper edge of the strip, said rabbet being of a width and height sufficient to receive the mounting clips 20 employed.

As shown in Figs. 7 and 8, each of the mounting clips 20 consists preferably of a metal rod or wire bent so that its end portions 20a extend vertically and at the bends at their lower ends connect with horizontal portions 20b connected by second bends with the upper ends of second vertical portions 20c connected by bends at their lower ends with the ends of the lower horizontal member 20d of the clip, each of said bends being preferably a right angle. In use, the portions 20c and 20d enter the rabbet 17a, the portions 20b extend across the upper edge of the mounting strip 17, and the end portions 20a extend upwardly through the apertures 11a and 12a in the lugs 11 and 12 of the tile 10 being mounted, which rest on the upper edge of the strip 17, the portions 20b of the clip being contained in the grooves 11b and 12b in the lower surfaces of the supporting lugs 11 and 12. The upper end portions 20a of the clip 20 are of a length to extend vertically through the lugs 11 and 12 of the tile being mounted, and also a substantial distance above said lugs to enter the apertures 13a and 14a 30 in the lower lugs 13 and 14 of a second tile when the latter is placed above the tile being mounted, thereby alining the tiles vertically. The portion 20d of the clip 20 is of a length to space the end portions 20a an amount equal to the horizontal 35 spacing of the apertures 11a and 12a and also of the apertures 13a and 14a.

After the strips 17 have been secured to the wall 18 as described, the ends 20a of one of the clips 20, are inserted through the upper lugs 11 and 12 on each of the tiles 10, each tile is dressed on its back face with sufficient cement or mortar to fill the space between the tile and the wall when the tile is in place, the tile is then raised above its mounting strip 17 sufficiently to clear the clip 20 and the tile is pressed against the wall until its lugs engage the wall, bringing the portions 20c and 20d of the clip directly over the rabbet 17a in the strip 17, and then the tile is pressed down until its upper lugs rest firmly against the upper edge of the mounting strip 17, which moves the portions 20c and 20d of the clip into the rabbet 17a, at the same time moving the apertures 13a and 14a in the lower lugs 13 and 14 of the tile being mounted, onto the upper projecting ends of the upper end portions 20a of the clip 20 supporting the tile immediately below the tile being mounted, thus effecting the relation between the wall 18, the mounting strips 17 thereon, the mounting clips 20 and the tiles 10 mounted on the wall, which is illustrated in Figs. 1 and 2. The length of the clip portions 20b is such as to hold the rear ends of the tile lugs snugly against the wall 18.

The mounting strips 17 thus aline the mounted tiles horizontally and support the weight of said tiles while the mounting cement or mortar is plastic, and the mounting clips at the same time hold the tiles in proper position on and against the wall and also hold the mounted tiles in vertical alinement. The proper alinement of the tiles is thus automatically effected both horizontally and vertically without measurement, skill or delay of any kind on the part of the workman, and the work of setting the tiles proceeds 75

more rapidly, more accurately and with much less required skill than is possible in setting tiles in the usual manner without mounting devices.

In Fig. 9, I illustrate a modified form of mounting clip 21, which is adapted for use under conditions making it impracticable to use the mounting clips 20 above described. The clip 21 consists of a metal rod or wire having an upper end portion 21a similar to the portion 20a, a horizontal portion 21b like the portion 20b, a second vertical portion 21c like the portion 20c, and a short horizontal lower end portion 21d like one end of the portion 20d, the clip 21 being in effect the same as one end of the clip 20, retaining preferably a sufficient amount of the lower horizontal portion 20d of the clip 20, to form the lower end portion 21d of the clip 21, to enter the rabbet 17a and prevent angular movement of the clip 21 about a vertical axis. The several portions of the clip 21 are for the purpose and operate in the manner above described for the corresponding portions of the clip 20.

A practical advantage resulting from making the clips 20 and 21 of metal rod or wire of relatively small diameter or cross-section as illustrated, is that the clips may readily be cut by cutting pliers where special conditions require, for example, with the upper course of tiles, the projecting ends of the clips may be cut off to avoid interference with finishing bands or strips.

While in the drawing I illustrate an embodiment of my invention applicable without change of any kind to square and rectangular tiles, it will be understood that with obvious changes it may be employed with tiles of any shape adapted to be mounted in regular rows, whether the rows extend precisely as described or not.

While I have shown my invention in the particular embodiment above described, I do not limit myself thereto as I may employ equivalents thereof without departing from the scope of the appended claims.

What I claim is:

1. The combination of horizontally disposed mounting strips, tiles having upper and lower back lugs above and below said strips respectively for engagement with a wall, and metal clips connecting said strips with the upper lugs of said tiles, said upper and lower lugs having apertures extending vertically therethrough and symmetrically spaced and disposed whereby the upper and lower portions of each of said tiles are interchangeable, and each of said clips having a mid-portion in retaining engagement with one of said strips and having vertical end portions spaced to align with the upper apertures of each of said tiles and entering the upper apertures of one of said tiles to hold the latter in place on the wall, the upper edges of said mounting strips being spaced an amount substantially equal to the height of said tiles.

2. The combination of horizontally disposed mounting strips, tiles having upper and lower back lugs above and below said strips respectively for engagement with a wall, and metal clips connecting said strips with the upper lugs of said tiles, said upper and lower lugs having apertures extending vertically therethrough and symmetrically spaced and disposed whereby the upper and lower portions of each of said tiles are interchangeable, and each of said clips having a mid-portion in retaining engagement with one of said strips and having vertical end portions spaced to align with the upper apertures of each of said tiles and entering the upper apertures of one of

said tiles to hold the latter in place on the wall, the upper edges of said mounting strips being spaced an amount substantially equal to the height of said tiles, each of said strips having a rabbet in the upper portion of its rear surface and extending through its upper edge, and the mid-portion of each of said clips being vertical and contained in the rabbet in one of said strips.

3. The combination of horizontally disposed mounting strips, tiles having upper and lower back lugs above and below said strips respectively for engagement with a wall, and metal clips connecting said strips with the upper lugs of said tiles, said upper and lower lugs having apertures extending vertically therethrough and symmetrically spaced and disposed whereby the upper and lower portions of each of said tiles are interchangeable, and each of said clips having a mid-portion in retaining engagement with one of said strips and having vertical end portions spaced to align with the upper apertures of each of said tiles and entering the upper apertures of one of said tiles to hold the latter in place on the wall, the upper edges of said mounting strips being spaced an amount substantially equal to the height of said tiles, the vertical end portions of said clips extending above the upper lug apertures containing them and into the lower lug apertures of tiles respectively above them, thereby alining said tiles vertically.

4. The combination of horizontally disposed mounting strips, tiles having upper and lower back lugs above and below said strips respectively for engagement with a wall, and metal clips connecting said strips with the upper lugs of said tiles, said upper and lower lugs having apertures extending vertically therethrough and symmetrically spaced and disposed whereby the upper and lower portions of each of said tiles are interchangeable, and each of said clips having a mid-portion in retaining engagement with one of said strips and having vertical end portions spaced to align with the upper apertures of each of said tiles and entering the upper apertures of one of said tiles to hold the latter in place on the wall, the upper edges of said mounting strips being spaced an amount substantially equal to the height of said tiles, each of said strips having a rabbet in the upper portion of its rear surface and extending through its upper edge, and the mid-portion of each of said clips being vertical and contained in the rabbet in one of said strips, the vertical end portions of said clips extending above the upper lug apertures containing them and into the lower lug apertures of tiles respectively above them, thereby alining said tiles vertically.

5. The combination of horizontally disposed mounting strips, tiles having integral upper and lower back lugs above and below said strips respectively for engagement with a wall, and clips comprising bent metal rods connecting said strips with the upper lugs of said tiles, said lugs having apertures extending vertically therethrough, and each of said clips having spaced and vertical end portions alining with and engaging the upper apertures in one of said tiles and having lower bends connecting with first horizontal portions substantially perpendicular to the plane of said end portions and in turn connected by bends with vertical mid-portions joining a second horizontal and mid-portion of the clip, said mid-portions being substantially parallel with the plane of said end portions with said second horizontal

portion below said first horizontal portions and back of one of said strips.

6. The combination of horizontally disposed

- 5 mounting strips, tiles having integral upper and lower back lugs above and below said strips respectively for engagement with a wall, and clips comprising bent metal rods connecting said strips with the upper lugs of said tiles, said lugs having apertures extending vertically therethrough, and

10 each of said clips having spaced and vertical end portions alining with and engaging the upper apertures in one of said tiles and having lower bends connecting with first horizontal portions substantially perpendicular to the plane of said

15 end portions and in turn connected by bends with vertical mid-portions joining a second horizontal and mid-portion of the clip, said mid-portions being substantially parallel with the plane of said end portions with said second horizontal portion below said first horizontal portions and back of one of said strips, each of said strips having a rabbet in the upper portion of its rear surface containing the vertical and horizontal mid-portions of corresponding ones of said clips.

20 7. The combination of horizontally disposed mounting strips, tiles having integral upper and lower back lugs above and below said strips respectively for engagement with a wall, and clips comprising bent metal rods connecting said

25 strips with the upper lugs of said tiles, said lugs having apertures extending vertically therethrough, and each of said clips having spaced and vertical end portions alining with and engaging the upper apertures in one of said tiles

30 and having lower bends connecting with first horizontal portions substantially perpendicular to the plane of said end portions and in turn connected by bends with vertical mid-portions joining a second horizontal and mid-portion of the

35 clip, said mid-portions being substantially parallel with the plane of said end portions with said second horizontal portion below said first horizontal portions and back of one of said strips, each of said strips being narrower vertically

40 than the vertical distance between the upper and lower lugs of the tiles mounted thereon by at least the vertical extent of the vertical mid-portions of the clips holding the tiles on said strip.

45 8. The combination of horizontally disposed mounting strips, tiles having integral upper and lower back lugs above and below said strips respectively for engagement with a wall, and clips comprising bent metal rods connecting said

50 strips with the upper lugs of said tiles, said lugs having apertures extending vertically therethrough, and each of said clips having spaced and vertical end portions alining with and engaging the upper apertures in one of said tiles

55 and having lower bends connecting with first horizontal portions substantially perpendicular to the plane of said end portions and in turn connected by bends with vertical mid-portions joining a second horizontal and mid-portion of the

60 clip, said mid-portions being substantially parallel with the plane of said end portions with said second horizontal portion below said first horizontal portions and back of one of said strips, the upper apertures of said tiles having the same

65 spacing as the lower apertures thereof, and the end portions of said clips extending above the tiles held thereby and into the lower apertures of the tiles respectively above the tiles so held and thereby alining said tiles vertically.

70 9. The combination of horizontally disposed

75

mounting strips, tiles having integral upper and lower back lugs above and below said strips respectively for engagement with a wall, and clips comprising bent metal rods connecting said strips with the upper lugs of said tiles, said lugs having apertures extending vertically therethrough, and each of said clips having spaced and vertical end portions alining with and engaging the upper apertures in one of said tiles and having lower bends connecting with first horizontal portions substantially perpendicular to the plane of said end portions and in turn connected by bends with vertical mid-portions joining a second horizontal and mid-portion of the clip, said mid-portions being substantially parallel with the plane of said end portions with said second horizontal portion below said first horizontal portions and back of one of said strips, the upper apertures of said tiles having the same spacing as the lower apertures thereof, and the end portions of said clips extending above the tiles held thereby and into the lower apertures of the tiles respectively above the tiles so held and thereby alining said tiles vertically, each of said strips having a rabbet in the upper portion of its rear surface containing the vertical and horizontal mid-portions of corresponding ones of said clips.

10. The combination of horizontally disposed mounting strips, tiles having integral upper and lower back lugs above and below said strips respectively for engagement with a wall, and clips comprising bent metal rods connecting said strips with the upper lugs of said tiles, said lugs having apertures extending vertically therethrough, and each of said clips having spaced and vertical end portions alining with and engaging the upper apertures in one of said tiles and having lower bends connecting with first horizontal portions substantially perpendicular to the plane of said end portions and in turn connected by bends with vertical mid-portions joining a second horizontal and mid-portion of the clip, said mid-portions being substantially parallel with the plane of said end portions with said second horizontal portion below said first horizontal portions and back of one of said strips, the upper apertures of said tiles having the same spacing as the lower apertures thereof, and the end portions of said clips extending above the tiles held thereby and into the lower apertures of the tiles respectively above the tiles so held and thereby alining said tiles vertically, each of said strips having a rabbet in the upper portion of its rear surface containing the vertical and horizontal mid-portions of corresponding ones of said clips, each of said strips being narrower vertically than the vertical distance between the upper and lower lugs of the tiles mounted thereon by at least the vertical extent of the vertical mid-portions of the clips holding the tiles on said strip. 60

11. A tile of ceramic material including a body portion having integral upper and lower lugs extending perpendicularly from its back surface, said lugs having apertures extending vertically through them for receiving mounting clips, said upper apertures having substantially the same spacing and relation to said body portion as said lower apertures, whereby the upper and lower portions of said tile are interchangeable in mounting the same. 65 70

12. A tile of ceramic material including a body portion having first integral upper and lower lugs extending perpendicularly from its back surface, 75

5 said lugs having apertures extending vertically through them for receiving mounting clips, said upper apertures having substantially the same spacing and relation to said body portion as said lower apertures, whereby the upper and lower portions of said tile are interchangeable in mounting the same, and second integral lugs in line horizontally with said upper and said lower lugs for anchoring purposes.

10 13. A tile of ceramic material including a body portion having first integral upper and lower lugs extending perpendicularly from its back surface, said lugs having apertures extending vertically through them for receiving mounting clips, said upper apertures having substantially the same spacing and relation to said body portion as said lower apertures, whereby the upper and lower portions of said tile are interchangeable in mounting the same, and second integral lugs in line horizontally with said upper and said lower lugs for anchoring purposes, the lower surfaces of said upper first and second lugs being in alinement horizontally and the upper surfaces of said lower first and second lugs being also in alinement horizontally, said second lugs being of less height vertically than said first lugs.

14. A tile of ceramic material including a body portion having integral upper and lower lugs extending perpendicularly from its back surface, said lugs having apertures extending vertically through them for receiving mounting clips, said upper apertures having substantially the same spacing and relation to said body portion as said lower apertures, whereby the upper and lower portions of said tile are interchangeable in mounting the same, said upper lugs having grooves in their lower surfaces extending rearwardly from the apertures therein and said lower lugs having similar grooves in their upper surfaces to receive parts of said mounting clips.

15. The combination of horizontally disposed mounting strips, tiles having integral upper and lower back lugs above and below said strips respectively for engagement with a wall, and clips comprising bent metal rods connecting said strips with the upper lugs of said tiles, said lugs having apertures extending vertically therethrough, and each of said clips having spaced and vertical end portions alining with and engaging the upper apertures in one of said tiles and having lower bends connecting with first horizontal portions substantially perpendicular to the plane of said end portions and in turn connected by bends with vertical mid-portions joining a second horizontal and mid-portion of the clip, said mid-portions being substantially parallel with the plane of said end portions with said second horizontal portion below said first horizontal portions and back of one of said strips, each of said upper lugs having

in its lower surface a groove extending rearwardly from the aperture therein to receive a first horizontal portion of one of said clips.

16. The combination of horizontally disposed mounting strips, tiles having integral upper and lower back lugs above and below said strips respectively for engagement with a wall, and clips comprising bent metal rods connecting said strips with the upper lugs of said tiles, said lugs having apertures extending vertically therethrough, and each of said clips having spaced and vertical end portions alining with and engaging the upper apertures in one of said tiles and having lower bends connecting with first horizontal portions substantially perpendicular to the plane of said end portions and in turn connected by bends with vertical mid-portions joining a second horizontal and mid-portion of the clip, said mid-portions being substantially parallel with the plane of said end portions with said second horizontal portion below said first horizontal portions and back of one of said strips, the upper apertures of said tiles having the same spacing as the lower apertures thereof, and the end portions of said clips extending above the tiles held thereby and into the lower apertures of the tiles respectively above the tiles so held and thereby alining said tiles vertically, each of said upper lugs having in its lower surface and each of said lower lugs having in its upper surface a groove extending rearwardly from the aperture therein to receive a first horizontal portion of one of said clips.

17. The combination of horizontally disposed mounting strips, tiles having first upper and lower back lugs above and below said strips respectively for engagement with a wall, and metal clips connecting said strips with the upper lugs of said tiles, said upper and lower lugs having apertures extending vertically therethrough and symmetrically spaced and disposed whereby the upper and lower portions of each of said tiles are interchangeable, and each of said clips having a mid-portion in retaining engagement with one of said strips and having vertical end portions spaced to aline with the upper apertures of each of said tiles and entering the upper apertures of one of said tiles to hold the latter in place on the wall, the upper edges of said mounting strips being spaced an amount substantially equal to the height of said tiles, said tiles having second lugs in line horizontally with said upper and said lower lugs for anchoring purposes, the lower surfaces of the upper first and second lugs of each tile being in alinement and the upper surfaces of the lower first and second lugs thereof being also in alinement for supporting purposes, said second lugs being of less extent vertically than said first lugs.

CARL F. GLASER.
